UNITED STATES PATENT OFFICE.

HENRY A. R. HORTON, OF GREENVILLE, TEXAS.

DESIGN FOR A BADGE.

SPECIFICATION forming part of Design No. 17,483, dated July 26, 1887.

Application filed June 8, 1887. Serial No. 240,668. Term of patent 14 years.

To all whom it may concern:

Be it known that I, HENRY A. R. HORTON, a citizen of the United States, residing at Greenville, in the county of Hunt and State of Texas, have invented a new and useful Improvement in Design for Badges, of which the following is a specification.

My invention relates to a design for badges; and it consists in the ornamentation upon the face of the badge, which will be more fully hereinafter described, and pointed out in the claims.

My design is illustrated in the accompanying drawings, wherein like letters of reference indicate similar parts in the several views, and in which—

As shown in the accompanying drawings, the badge is formed of a circular plate or disk, A, at the upper portion of which is a segmental field, and immediately below a rising sun is represented, and below the rising sun an arm and hand are shown. Twining around the arm and hand and held by the hand is a serpent, and adjacent to the head of the serpent one end of a chain is secured, the other end of said chain being attached to the shackle of a padlock, which is shown at the lower portion of the plate A, below the hand, arm, and serpent. 30

Having thus set forth my design, I claim—

1. The design for a badge herein shown and described, the same consisting of a circular body ornamented upon one side with a field, rising sun, arm and hand entwined by a serpent, and a chain secured near the head of the serpent at one end and at its other end to the shackle of a padlock, substantially as set forth. 35

2. The design for a badge herein shown and described, consisting of a plate or body ornamented on one side with the representation of a rising sun, an arm and hand, a serpent, and a shackle and lock, substantially as set forth. 40 45

In testimony that I claim the foregoing as my own I have hereto affixed my signature in presence of two witnesses.

HENRY A. R. HORTON.
